YORK.

GAS CUTTING APPARATUS.

1,291,735.

Specification of Letters Patent. Patented Jan. 21, 1919.

Application filed October 16, 1917. Serial No. 196,792.

To all whom it may concern:

Be it known that we, HARRISON BIRD and FREDRICK J. MAEURER, citizens of the United States, and both residents of Chicago, in the county of Cook and State of Illinois, have invented new and useful Improvements in Gas Cutting Apparatus, of which the following is a specification.

The invention relates to gas cutting apparatus of the type disclosed in Patent No. 1,118,183, granted November 24, 1914, to Worthy C. Bucknam, comprising a portable, mechanically-driven, torch-bearing carriage adapted to run upon an underlying surface and to cut upon either straight or curved lines, the latter through the provision of a center which may be brought into engagement with the surface; and the object is to equip such apparatus with means whereby it may be used to cut various irregular or desired shapes through the aid of a suitable templet. To this end the carriage is provided with a flexible arm, bearing the torch, and a roller to coöperate with the edge of the templet.

In the accompanying drawings illustrating the invention:

Figure 1 is a rear elevation of the apparatus with parts broken away for the sake of clearness of illustration and economy of space. It will be understood that, when the carriage is operating with the attachment, the center 14 is depressed into engagement with the underlying surface and the wheel 6 is removed therefrom.

Fig. 2 is a plan view with portions broken away.

The carriage 2, while of more modern form than that disclosed in the patent aforementioned, is the same in essentials and may be said, is the same in essentials and may be described briefly. It comprises a platform 3, on which is mounted a small electric motor 4. The carriage has two front wheels 5 and 6, and preferably a single rear wheel 7 in line with the wheel 5. 8 is a horizontal radius rod secured to the forward part of the carriage and projecting beyond the side remote from the wheels 5 and 7. This rod is shown as constituting the support for the wheel 6. The driving power is applied to the front wheels through a change-speed gearing contained in a case 9 and forming no part of this invention, a vertical worm shaft 10, and a transverse shaft 11 bearing

pinions 12 meshing with gears 13 united to 55 the side wheels.

Adjustable so as to be set at various points along the radius rod is a center 14, which may be screwed down into engagement with the work or other underlying surface. A 60 counterweight 15 is placed upon the rod beyond the center.

Rising from the front inner corner portion of the carriage is the post 16, from which the torch is adjustably supported. In the 65 present instance this post serves for the attachment of a jointed arm 17, in the outer portion of which the torch 18 is suitably mounted. This arm preferably comprises two sections 19 and 20 pivotally connected 70 to each other at 21. The inner section 19 has a split clamp collar or hub 22, whereby it may be adjusted angularly about the post 16. The jointed arm 17 enables the torch to follow the outline of a suitable templet, such as 75 indicated for example at 23; and to this end the arm carries, in addition to the torch, a roller 24 adjacent the torch tip to travel against the edge of the templet. This roller may find its immediate support upon the 80 torch, to which it may be detachably secured by a clamp 25. A spring 26 at the joint 21 tends to contract the arm so as to hold the roller 24 in contact with the edge of the templet. It will thus be seen that, while 85 the carriage describes a circle, the torch in its cut will follow a path determined by the templet. The templet may be the edge of the underlying surface upon which the carriage travels, or it may be a separate piece. 90

In conclusion, it is to be understood that we do not limit ourselves to the specific construction illustrated, as other embodiments may be devised.

What we claim as new is:

1. In a gas cutting apparatus, the combination of a portable self-supporting mechanically-driven wheeled carriage adapted to run upon an underlying surface, a point center connected therewith and adapted to 100 be engaged with the work to cause the same to describe a circle, and a jointed torch-bearing arm extending from the carriage adapted to extend and contract and having side bearing means to coöperate with a suitable templet to guide the torch automatically in other than a circular course. 105
2. In a gas cutting apparatus, the combi-

nation of a portable self-supporting mechanically-driven wheeled carriage adapted to run upon an underlying surface, a center connected therewith to cause the same to 5 describe a circle, a jointed arm extending from the carriage adapted to extend and contract, a cutting torch supported by the arm, a roller adjacent the torch to travel against a suitable templet, and a spring act-
10 ing upon the arm.

3. In a gas cutting apparatus, the combination of a portable self-supporting me-

chanically-driven wheeled carriage adapted to run upon an underlying surface, a center connected therewith to cause the same to 1 describe a circle, a pivotally jointed torch-bearing arm adapted to extend and contract having an angularly adjustable mounting on the carriage and means to coöperate with a suitable templet, and a spring acting 2 upon the arm.

HARRISON BIRD.
FREDRICK J. MAEURER.
